CRIMPED COAXIAL CABLE TERMINATION

Carl W. Concelman, Danbury, Conn., assignor to Amphenol-Borg Electronics Corporation, Broadview, Ill., a corporation of Delaware

Filed Nov. 16, 1961, Ser. No. 152,752

5 Claims. (Cl. 174—89)

This invention relates to an improved electrical connector designed for connection with electrical coaxial cable and, in particular, relates to means for fastening such cable to the connector and to provide a good ground connection for the braid wire.

It is a principal object of the invention to provide a coaxial connector structure incorporating an improved clamping end for providing a good mechanical and electrical connection to the cable. The cable clamping structure is especially well suited to small coaxial cables. With present art, it is difficult to provide a cable clamping action that will withstand cable flexing and handling as normally encountered in field usage. In the instant invention, the cable pull-out force approaches the ultimate breaking strength of the cable. Although shown and described for small cables, the construction is equally well suited for larger cables and offers comparable advantages.

It is a further object of the invention to provide a coaxial connector for connection with electrical coaxial cable and, in particular, wherein the improvement resides in clamping means incorporated in the structure of the connector. The improved clamping means is equipped to provide a good low resistance contact between the cable braid wire and the connector shell. The clamping means is also characterized to clamp the cable without any appreciable deformation to the cable to avoid impedance discontinuities.

It is a further object of the invention to provide a coaxial connector designed for connection with electrical coaxial cable wherein the connector includes a mechanically simple structure for clamping the cable to the connector by a standard crimping tool and whereby such attachment is reliable in holding the cable fastened to the connector and said cable is gripped against pull-out.

It is a further object of the invention to provide a coaxial connector clamping structure that does not appreciably deform the cable clamped thereby to avoid impedance discontinuities. The clamping structure employs a longitudinally slotted ferrule or clamping sleeve mounted on the cable, which sleeve is dimensioned so that a hexagonal crimp closes its slot to prevent further closure of the clamping sleeve over the cable.

It is a further object of the invention to provide a small, neat appearance cable clamp structure that does not require the addition of an elastic boot or sleeve to present a finished appearance.

It is a further object of the invention to provide a coaxial connector structure incorporating an improved clamping end for fastening electrical coaxial cable to such connector by a crimping tool and wherein the structure of such clamping end is relatively simple with respect to fabrication and use and is particularly suitable for connectors and cables of small size, but is not limited to small size transmission line cable and coaxial connector components.

Further objects and advantages will become apparent from the following description of the invention taken in conjunction with the figures, in which:

FIG. 1 is a longitudinal elevation in section of a connector incorporating the principles of the invention prior to clamping;

FIG. 2 is a fragmentary section illustrating the clamp-

2

ing components of the connector acting upon the cable after the crimping action; and

FIG. 3 is a perspective view of the clamping sleeve prior to crimping.

Reference is made to the figures for an embodiment of a connector 10 incorporating the principles of the invention. The longitudinal shell 11 is a conductive tubular body which defines the outer conductor of connector 10. Shell 11 has a through bore 12 extending between its opposite and forward rearward ends 13, 14. A cylindrical and relatively hollow conductive member 15 is retained in the bore of shell body 11. The front end of member 15 is turned in to capitate an insulator member 16. Insulator 16 serves to captivate an inner conductor contact 17. Contact 17 is provided with an outer radial tooth 18 which bites into insulator 16. Member 15 has a radial flat wall 19. The other side of wall 19 abuts against an internal shoulder 21 in bore 12. The section 20 of bore 12 between wall 19 and shell open end 14 is equipped to receive the coaxial cable 22 to be connected to connector 10.

Connector 10 is designed to connect to electrical coaxial cable 22 depicted as having an inner conductor 23 surrounded by a coaxial insulator 24, which insulator 24 in turn is surrounded by an outer conductor braid 25, whereas braid 25 is covered by an outer insulating and protective sheath 26.

The remainder of the connector clamping means includes a tubular wall ferrule or sleeve 27 extending axially between opposite first and second ends 28, 29. Sleeve 27 may be made of a deformable metal, such as brass. Sleeve 27 has a through bore 30 for mounting same over cable 22. The front portion of sleeve bore 30 is serrated by threads or ridges 31 to provide a good grip around the outer cable surface after a crimping action is completed. Tubular sleeve 27 also has a longitudinal slot 32 extending along its wall between its opposite ends 28, 29. Sleeve 27 is dimensioned for easy mounting over cable 22 prior to the crimping step.

A radially raised V-shaped ridge 33 extends annularly about the outer surface of sleeve body 27. Ridge 33 is made up of two inclined faces 33a, 33b. The tubular wall of shell 11 includes a corresponding V-shaped annular recess 34 intermediate the ends of bore section 20. Recess 34 is formed by inclined faces 34a, 34b.

In preparation of attaching cable 22 to connector 10, cable sheath 26 is cut short to terminate within the sleeve front end 28 upon mounting the latter on cable 22, as shown in FIG. 1. The end of cable insulator 24 is cut off to bare a length of cable inner conductor 23 for attachment to connector contact 17. The portion of cable braid extending from the sleeve front end 28 is folded around and pulled back over the outer surface of the sleeve wall. The end of braid 25 may be cut off to terminate same to the left of sleeve ridge 33. Furthermore, the forward end of cable insulator 24 passes through a central opening in wall 19 and is cut square to abut against a stop shoulder in the interior of bore 12 provided by the rear of contact 17 and insulator 16 upon insertion of cable 22 and the sleeve 27 mounted thereon into shell bore section 20. When the assembly of cable 22 and sleeve 27 is so inserted, the folded over portion of braid 25a is wedged between radial wall 15 and the sleeve front end 28, whereas the pulled back portion of braid 25b is wedged between sleeve 27 and the bore surface of shell section 20.

Ridge 33 and recess 34 are predeterminedly located along their respective bodies so that upon seating the assembly of cable 22 and sleeve 27 in bore section 20 prior to crimping action, the vertical center line 35 of recess 34 is slightly to the left of the vertical center line 36 of ridge

33, as shown in FIG. 1, whereby the rear inclined ridge and recess faces 33b and 34b, respectively, are juxtaposed and closely spaced apart.

A crimping tool, not shown, is then inserted over the portion 37 of the shell tubular wall axially surrounding bore section 20. The crimping tool is equipped to crimp hexagonally wall portion 37 circumferentially 360° about its axis. The crimp extends longitudinally the length of wall portion 37. Crimping action constricts this section 37 of tubular wall along its longitudinal axis and circumferentially 360° about its longitudinal axis to cause inclined recess face 34b to close against inclined ridge face 33b. By virtue of the geometry of the V-shaped ridge 33 and recess 34, a force is transmitted to sleeve face 33b from shell face 34b which pushes sleeve 27 in a forward direction to clamp braid 25 tightly against wall 19. Since the crimping action is applied circumferentially 360° around shell wall section 37, the constricting force, depicted by the arrows in FIG. 3, also closes sleeve slot 32 which accomplishes a tight grip of cable 22 by serrations 31. Furthermore, closing of recess face 34b against sleeve face 33b also locks sleeve 27 in shell 11 to prevent rearward movement of sleeve 27 out from shell 11.

Prior to crimping, inner conductor 23 is electrically fastened to contact 17 by soldering 38 in accordance with well-known practices. Contact 17 is also captivated coaxially within shell 11 by a second insulator member 39. Member 39 is held by a turned in wall 49 of shell 11. The forward end of shell 11 includes a threaded coupling nut 41 for attaching connector 10 to a mating connector.

The clamping end of connector shell 11 may be standardized with respect to its dimensions for use with cables of different sizes. For a smaller diameter cable, clamping sleeve 27 will have a relatively thicker cross-sectional wall, that is to say, the dimension A will be greater to accommodate smaller cable. Conversely, the cross-sectional thickness A of sleeve wall is decreased to accommodate cable of larger diameter.

FIG. 2 shows the clamped end of connector after crimping. The outer surface of connector wall 37 is partially flattened to a hexagonal shape by the crimping tool. The force is transmitted to close recess face 34b against ridge face 33b. The force tends to push sleeve 27 forward to squeeze the radial portion of braid 25a between sleeve front end 28 and wall 19; whereas, the pulled back section of braid 25b is squeezed between the cylindrical wall of sleeve 27 and the surface of bore section 20. This assures a good low resistance contact between cable braid 25 and connector shell 11. The crimping action causes the sleeve serrations 31 to close upon cable sheath 26 when slot 32 closes. However, closure of slot 32 stops further constriction of sleeve 27 against cable 22 to prevent deformation of the cable insulation 24 and a resulting impedance discontinuity. The assembly is also locked by virtue of the geometry of the contiguous inclined faces 33b, 34b to prevent escape of sleeve 27 and accidental pull out of cable 22.

Although recess 34 and ridge 33 are V-shaped in the illustrated embodiment, it would be entirely within the scope of the invention to employ a semi-circular recess in the interior wall of shell portion 37 and a correspondingly shaped semi-circular ridge or shoulder on the wall of sleeve 27 to achieve the same operation provided by the illustrated recess 34 and ridge 33. Furthermore, the principles of the illustrated cable clamp also may be used to attach a connector to coaxial cable having a solid tubular metal jacket as its outer conductor in place of a braided shield and protective jacket as illustrated herein. For cable with an outer solid tubular metal jacket, sleeve 27 closes to grip tightly the outer metal jacket upon crimping, whereby the forward end of such jacket will bottom against wall 19 to effect a good ground connection to connector shell 11. In addition, a good ground con-

nection is also achieved by increasing the dimension "A" of sleeve so that after crimping, the outer surface of sleeve 27 also makes good contact with the surrounding wall portion 37. Further electrical connection is obtained by recess face 34b closing against ridge face 33b after crimping. It is also submitted that the principles of the foregoing clamp structure is applicable to non-electrical coupling devices, for example, for connecting tubular piping to a coupling device, which device includes the features of the sleeve 27 and recess and ridge 34, 33.

It is intended that all matter contained in the above description or shown in the accompanying drawings shall be interpreted as illustrative and not in a limiting sense.

What is claimed is:

1. A coaxial connector clamping means for fastening an electrical coaxial cable to the connector wherein the cable has a conductive inner conductor surrounded by successive layers of insulator, a braided outer conductor and an insulator sheath, the combination comprising, a tubular wall conductive shell defining the connector outer conductor, said shell having an axial through bore extending from an open rearward end to its front end, the axial section of bore adjacent said shell rearward end being equipped for receiving the end of coaxial cable to be connected to said connector, radial wall means in the interior of said bore section and confronting the open rearward end of said bore, said bore section also having an inclined face recessed in the wall of said shell, said inclined face being at an angle with the axis of said bore substantially to confront the interior end of said section, a tubular wall sleeve of deformable material having an axial through bore for mounting same over the end of cable to be inserted into said connector, said sleeve having a longitudinal slot extending between its front and rear ends and radially through its wall, the cable sheath being cut off to terminate within said sleeve and the cable braid extending out from the front end of said sleeve and folded back over the outer surface of said sleeve wall for insertion of the cable and said sleeve mounted thereon in seated relationship in said connector bore section, a portion of the folded back braid being pressed between said radial wall and the front end of said sleeve, means on said sleeve extending substantially radially for confronting said inclined face to effect mutual engagement therebetween characterized to urge said sleeve in an axially forward direction in said shell bore upon a circumferential constricting force being applied to said shell, said sleeve being constricted to close upon said cable upon circumferentially crimping the wall of said shell surrounding said bore section, constriction of said sleeve being taken up by closure of said slot, said crimping force also causing said inclined face to engage said means on said sleeve for urging said sleeve in a forward direction to clamp said braid tightly against said radial wall and to lock said sleeve in said connector.

2. A coaxial connector clamping means for fastening an electrical coaxial cable to the connector wherein the cable has an inner conductor and a braid outer conductor separated by insulator means, the combination comprising, a tubular wall shell defining the connector outer conductor, said shell having an internal section of bore extending from the open end of said shell, shoulder means in the interior of said bore section, said bore section being equipped for receiving the coaxial cable to be connected to said connector, said bore section having a recessed inclined face extending into the wall of said shell, said face substantially confronting the interior of said bore section, a tubular wall sleeve of deformable material having an axial through bore between the front and rear ends of said sleeve for mounting said sleeve over the end of the cable to be inserted into said connector, slot means extending axially along said sleeve, the cable braid extending out from the front end of said sleeve and being folded back over the outer surface of said

sleeve wall for insertion of the cable and said sleeve mounted thereon in seated relationship in said connector bore, a portion of the folded back braid being pressed between said interior shoulder means and the front end of said sleeve, and means on said sleeve extending substantially radially for confronting said inclined face to effect mutual engagement therebetween characterized to urge said sleeve in an axially forward direction upon a circumferential constricting force being applied to said shell surrounding said bore section, constriction of said cable upon circumferentially crimping the wall of said shell surrounding said bore section, constricting of said sleeve is taken up by closure of said slot means, closure of said slot means substantially halts further constriction of said sleeve on said cable, the crimping force causes said inclined face to engage said means on said sleeve for urging said sleeve in a direction to clamp said braid against said shoulder and also to lock said sleeve in said connector.

3. A connector as defined in claim 2 wherein, the bore

of said sleeve including serrations for tightly gripping said cable upon constriction of said sleeve.

4. A connector as defined in claim 2 wherein, said recess is made up of juxtaposed faces defining an annular V-shaped recess, and said sleeve means including a radially raised ridge having inclined faces forming a V-shaped ridge juxtaposed said recess upon insertion of said sleeve into said bore section.

5. Means as defined in claim 4 wherein, said sleeve bore including serrations for tightly gripping said cable upon constriction of said sleeve, and the portion of the folded back braid over the outer surface of said sleeve wall being squeezed tightly between said sleeve and tubular wall of said shell upon crimping of same.
